TWIN-BARREL GUN WITH A DRUM AND A MULTISTATION RAMMER

John F. O'Brien, Springfield, Mass., assignor to the United States of America as represented by the Secretary of the Army

Filed Sept. 26, 1955, Ser. No. 536,791

5 Claims. (Cl. 89—155)

(Granted under Title 35, U.S. Code (1952), sec. 266)

The invention described herein may be manufactured and used by or for the Government for governmental purposes without the payment of any royalty thereon.

My invention relates to a twin-barreled revolver-type weapon and more particularly to a rammer therefor.

A gun having twin barrels for firing ammunition consisting of separate cases and projectiles is provided with a drum having alternate chambers for respectively inclosing the cases and projectiles. In operation a cartridge is fired in one of the barrels, after which the rammer is actuated and then the drum is rotated for discharge through the other one of the barrels, responsive to force of the discharge.

When a cartridge is combined at the breech of one barrel for discharge therethrough, a projectile is chambered in the drum chamber adjacent the other barrel and during the subsequent ramming the projectile is propelled from the adjacent chamber into the barrel and a case and another projectile are respectively charged into the pair of chambers rotationally precedent to the adjacent chamber so that during the following rotation of the drum the case is rotated in back of the barrel-inclosed projectile and the projectile in the drum is moved into alignment with the other one of the barrels.

It is the object of my invention, therefore, to provide a charger to accomplish such ramming.

Other aims and objects of my invention will appear from the following description thereof.

In carrying out my invention a gun provided with twin barrels and a six chamber cartridge drum is provided with a pair of rammers respectively related to opposite ones of the barrels for operation responsive to discharge of cartridges in the barrels. The rammers are respectively disposed in pairs of tracks and respectively provided with cylinders including double-acting pistons for alternate reciprocal operation responsive to discharge gases from the barrels.

Each of the rammers includes a projection for chambering a projectile in the relative one of the barrels when aligned therewith and a pair of projections for simultaneously charging a case and a projectile into the respective chambers rotationally precedent to the chamber from which the projectile is rammed into the aligned barrel.

For a more complete understanding of my invention reference is made to the following description thereof and the accompanying drawings in which:

Fig. 1 is an elevational view partly cut away of a gun incorporating my invention in battery position for the upper barrel before firing of cartridges 40 therethrough;

Fig. 2 is a similar view with the rammer at the end of the charging stroke;

Fig. 3 is a view along line 3—3 of Fig. 1;

Fig. 4 is a view along line 4—4 of Fig. 2; and

Fig. 5 is a fragmentary cross-section of the drum in battery position for the lower barrel.

Accordingly, a revolver-type gun 12 includes a receiver 14, twin barrels 16 and 18 secured thereon, a drum 20

2

rotatable on the receiver and a pair of similar rammers 22 axially slideable in receiver 14. Rollers 23 of rammers 22 engage slots 25 of receiver 14 to retain rammers 22 laterally therein.

5 Drum 20 includes chambers 24, 26, 28 and alternately disposed chambers 30, 32, and 34 for respectively inclosing cases 36 and projectiles 38 of split cartridges 40. The chambers are arranged in angularly-spaced diametral pairs for respectively inclosing a case and a projectile. 10 Cartridge 40 is shown in alignment with barrel 16 for discharge therethrough (Fig. 1), and a projectile 38 is shown in barrel 18 (Fig. 2). A case 36 and a projectile 38, respectively, are shown in chambers 26 and 30 (Fig. 2).

15 Each of the rammers 22 is secured to a double-acting piston 44 in a cylinder 46 by means of a link 47 pivoted at 49 in receiver 14. The rear ends of the cylinders are respectively connected to barrels 16 and 18 through tubes 53 for forward stroke operation of the pistons respectively responsive to discharge gases from the barrels. 20 The forward ends of the cylinders are connected to the opposite barrels through tubes 55 for return of the rammers to battery position.

A spring-biased projection 48 and a fixed projection 50 are provided on each rammer 22 for respectively charging a projectile 38 and a base 36 into chambers 30 and 26 during the forward stroke of piston 44. Projections 48 and 50 are constructed to dispose case 36 flush with the rear surface of drum 20 and projectile 38 in 30 an intermediate position in chamber 30, respectively.

Projectile chambers 30, 32 and 34 are provided with axial slits 51 and a projection 52 of rammer 22 includes a spring-biased arm 54 for insertion through the axial slit 51 of chamber 32 in the battery station of barrel 20 35 to ram projectile 38 from the chamber into such barrel responsive to the forward stroke of piston 44.

Gun 12 is provided with an actuator (not shown) in engagement with cam 56 of drum 20 for successively rotating the case and projectile chambers simultaneously 40 and alternately to alternate battery stations in axial alignment with relative ones of the barrels responsive to discharge of cartridges therein. The drum is rotated after charging and arm 54 is cammingly pivoted out of the projectile chambers for tangential engagement with drum 45 20 during the rotation. A torsion spring 58 is disposed between arm 54 and projection 52 to bias arm 54 through slit 51 of the following projectile chamber when in the battery station. Rear end 60 of spring 58 is slideable in a slot 62 of projection 52 and a stop 64 is provided in projection 52 for engagement with a pilot piston 66 to retain arm 54 in the projection.

The remaining rammer 22 operates similarly responsive to discharge of a cartridge through barrel 18, simultaneously to charge a case and a projectile in drum 20, 55 and ram a previously charged projectile into barrel 16.

The components of the rammers described operate at speeds comparable to the speeds of the rammer components of single-barreled guns.

Although a particular embodiment of the invention 60 has been described in detail herein, it is evident that many variations may be devised within the spirit and scope thereof and the following claims are intended to include such variations.

I claim:

65 1. In a gun including twin barrels and a drum provided with chambers in alternately disposed and angularly-spaced diametral pairs for respectively inclosing a case and a projectile of a split cartridge and disposed for battery station axial alignment of the chambers of one 70 of the pairs respectively with the barrels for discharge of a cartridge through one thereof, axial alignment of a projectile with the other of the barrels, and alignment in

respective charging stations of the case and projectile chambers rotationally subsequent to the projectile chamber of the one pair, and a rammer for simultaneously charging a case and a projectile into the charging station chambers and propelling the axial alignment projectile into the other of the barrels responsive to the discharge.

2. In a gun including twin barrels, and a drum provided with chambers in alternately disposed and angularly-spaced diametral pairs for respectively inclosing a case and a projectile of a cartridge and disposed for rotation for sequential disposal of the pairs in battery stations of alternate axial alignment of the chambers of the pairs with the barrels respectively for formation of a cartridge for discharge thereof through one of the barrels, for alignment of a projectile with the other of the barrels, and for simultaneous axial alignment in respective charging stations of the case and projectile chambers rotationally subsequent to the projectile chamber of the pair, a charging device comprising a pair of trifurcated rammers each provided with projections to charge a case and a projectile respectively into said charging station chambers and an arm to simultaneously propel a projectile from the battery station chambers into the other of the barrels responsive to the discharge of a cartridge.

3. In a gun including twin barrels, a receiver and a drum mounted to said receiver for rotation respective to said barrels, said drum being provided with chambers in alternately disposed and angularly-spaced diametral pairs for respectively inclosing a case and a projectile of a cartridge and disposed for sequential disposal of the pairs in battery stations of alternate axial alignment of the chambers of the pairs with the barrels for formation of cartridges for discharge thereof through one of the barrels, for alignment of projectiles with the other of the barrels, and for simultaneous axial alignment in respective charging stations of the case and projectile chambers

rotationally subsequent to the projectile chamber of the battery station pair, the projectile chambers having axial slits therein, a charging device comprising a pair of trifurcated rammers slidably disposed for reciprocation in the receiver and each being provided with projections to charge a case and a projectile respectively into said charging station chambers and a projection having a tip pivotable responsive to the rotation and spring-biased for projection into the axial slits to simultaneously propel a projectile from the battery station pair into the other of the barrels responsive to the discharge of a cartridge.

10 4. A charging device as in claim 3 with a pair of levers respectively pivotally connected between said rammers and the receiver and a pair of cylinders disposed thereon and provided with pistons respectively pivotally secured to said levers, said cylinders being respectively disposed for opposite rearward and forward communication with alternate ones of the barrels for the respective forward and rearward strokes of the reciprocation responsive to gases from the discharge.

15 5. In a gun including oppositely-disposed twin barrels and a drum provided with chambers in alternately-disposed and angularly-spaced diametral pairs for respectively inclosing a case and a projectile of a split cartridge and disposed for alternate battery station alignment of the chamber of one of the pairs respectively with the barrels for discharge of the cartridge and alignment of the remaining pairs of the chambers in respective charging stations, and a rammer for simultaneously charging the remaining pairs and the other of the barrels from the drum responsive to the discharge of a cartridge.
